UNITED STATES PATENT OFFICE

2,159,758

POWER PLANT

Günther Diedrich, Berlin-Reinickendorf, Germany, assignor to General Electric Company, a corporation of New York

Application September 13, 1937, Serial No. 163,688
In Germany September 24, 1936

1 Claim. (Cl. 60—11)

The present invention relates to power plants, more specifically to power plants including both internal combustion engines and elastic fluid turbines or engines.

5 The object of my invention is to provide an improved construction and arrangement whereby the economy and efficiency of such plants is materially improved.

10 For a consideration of what I believe to be novel and my invention, attention is directed to the following description and the claim appended thereto in connection with the accompanying drawing.

15 The single figure of the drawing illustrates a power plant embodying my invention.

In the present instance, I have shown my invention in connection with an air craft, more specifically a three-motored airplane 10 having three propellers 11, 12, and 13. The main propeller 12 is driven by an elastic fluid engine, in the present instance a turbine 13a, which receives elastic fluid from an elastic fluid generator or boiler 14. The propellers 11 and 13 are driven each by an internal combustion engine 15 and 16 respectively.

20 In order to utilize the available energy of the exhaust gases of the internal combustion engines 15 and 16, I provide in accordance with my invention, means for conducting such gases to a suitable point in the elastic fluid generator 14.

25 In the present example, an intermittent portion of the outer wall of the elastic fluid generator 14 is provided with annular channel 17 which forms a ring of nozzles 18 for properly directing exhaust gases of the combustion engines into the combustion space of the generator or boiler 14. The manifolds of the combustion engines 15, 16 are connected to the channel 17 of the boiler by conduits 19 and 20 respectively. The nozzles 18

30 are connected to the combustion space of the boiler at a point or points at which the temperatures within such space is of the order of the temperature of the exhaust gas of the engines. The boiler shown is of the forced-through type 35 having a heating element in the form of a single tube 21. Operating fluid is forced through the tube 21 by a boiler feed pump 22 having an inlet connected to a tank or reservoir 23 and an outlet 24 connected to the inlet of the tube 21.

40 The outlet of the tube 21 is connected by a conduit 25 to the inlet of the aforementioned elastic fluid turbine 13a. The latter discharges into an air-cooled surface type heat exchanger or condenser 26 whence the condensate is conducted 45 through a conduit 27 into the tank or reservoir

5 23. Means are provided for utilizing the available energy in the gases discharged from the elastic fluid generator or boiler. This means comprises a gas turbine 28 receiving gases from boiler 14 and driving a blower 29 having an impeller 30 secured to a shaft 31 which forms an extension of the shaft of the gas turbine. The blower 29 serves for furnishing air to maintain combustion in both the boiler and the internal combustion engines. To this end the blower 29 is 10 connected to the boiler and to the engine 16 by conduits 32 and 33. The conduit 32 includes a heat exchanger 34 receiving heat from the gases discharged from the gas turbine 28, the latter 15 being connected to the heat exchanger 34 by a conduit 35. The provision of a single blower for furnishing air under pressure to both the combustion space in the boiler and to the combustion engines is an important feature of my invention because it renders the operation of the plant more 20 economical than is possible by the provision of separate supercharging means for the combustion engine and blower means for the boiler.

25 Fuel is supplied to the boiler from a fuel tank 36 through a conduit 37, a fuel pump 38 and a burner 39. The conduit 37 includes a coil 31a located within the heat exchanger 34 whereby the fuel is preheated by the combustion gases flowing from the boiler through said heat exchanger 34.

30 The pumps 22 and 38 for forcing operating fluid and fuel into the boiler are preferably driven by engine means operated directly or indirectly by the exhaust gases of the boiler. In the present instance, these pumps are driven by motors 40 35 and 41 respectively which are energized through conductors 42 by an electric generator 43 driven from the gas turbine 28 through a gearing 44.

35 Thus with my invention I have accomplished an improved arrangement of combined elastic fluid generator and combustion engine power plants whereby the exhaust gases of both the combustion engine and the elastic fluid generator are fully utilized. The provisions of such plant is especially advantageous in connection with 45 aircraft because during starting operation the elastic fluid generator permits high overload and during normal operation the failure of one part of the plant permits operation by means of the other.

40 What I claim as new and desire to secure by Letters Patent of the United States is:

45 A power plant including the combination of a boiler forming a combustion space, a combustion engine, means including an annular channel and

a ring of nozzles formed in the wall of the boiler for conducting exhaust gases from the engine to points in the combustion space at which the temperature is the same as that of the combustion gases, and means for supplying fuel and air to the boiler, said means including a centrifugal

type compressor and a gas turbine receiving combustion gases from the boiler and driving the compressor, the gas turbine having a bucket wheel enclosed in the boiler casing.

GÜNTHER DIEDRICH.
